UNITED STATES PATENT OFFICE

2,584,854

BINDER

Charles Edward Emmer, Chicago, Ill., assignor to
General Binding Corporation, Chicago, Ill., a
corporation of Illinois

Application December 19, 1945, Serial No. 635,963

1 Claim. (Cl. 281—16)

1

The present invention relates to a loose-leaf binder, and more particularly to one in which the ring-like members are made of thermoplastic or other flexible material, which rings are integral with a backbone, the rings being formed to closed position to maintain the same closed in substantially permanent relation, and is directed to a construction of a thick binder for holding many sheets, cards or the like.

There are thick loose-leaf binders in use at the present time. These utilize a single tier of rings or the like, but present disadvantages in that, when open, the margins of the sheets, cards or the like along the openings pile up or stick up, making them unhandy for use.

The present invention overcomes this disadvantage by providing means forming a plurality of tiers of rings, laterally spaced with respect to the binder back, in order to arrange the sheets, cards or the like in groups, every group having a thickness which is considerably less than the thickest capacity of the binder.

The present invention does not reduce the capacity of a binder of given thickness but mounts the sheets, cards or the like in groups so that a desired sheet, card or the like may be more readily found, also, when the binder is open, the back of the binder is flat and the sheets, cards or the like of the several groups are presented in flatter manner than in a single tier binder, thus making it handier to find the sheets, cards or the like in question.

Embodiments of the present invention are illustrated in the accompanying drawing and the views thereof are as follows:

Figure 1 is a plan view of a binder equipped with the present invention, showing fragmental portions of the covers in open position, and illustrating three tiers of ring-like members secured to the back.

Figure 2 is an enlarged sectional view taken in the plane of line II—II of Figure 1, and showing D type rings.

Figure 3 is a similar sectional view showing split rings.

Figure 4 is a fragmental plan view of the binder equipped with another form of rings.

Figure 5 is an enlarged sectional view taken in the plane of line V—V of Figure 4.

The invention in the drawings will now be explained.

Referring to Figure 1, 10 designates the back of a loose-leaf binder, and 11 and 12 designate portions of the covers.

There are illustrated three tiers, A, B and C, of

thermoplastic ring members, the rings being known as D rings.

Every tier includes a backbone 13 having a plurality of fingers 14 extending from one side portion of the backbone, which are bent into substantially ring-shape after the sheets, cards, or the like, 15, have been applied to the fingers. A binding such as just described maintains the sheets, cards or the like, in substantially permanent binding relation.

Figure 3 illustrates a back 13 having three tiers D, E and F of plastic binding fingers. In this form every tier includes a backbone 16 having fingers 17 and 18 projecting from the side margins of the backbone which fingers are bent into substantially ring-shape, as shown, after a plurality of sheets or cards 19 have been applied to the rings.

It will thus be noted that within the width of the back 10 a plurality of tiers of rings have been secured, to receive groups of sheets, cards or the like, in which the total thickness of the sheets or cards in the several groups is substantially less than the thickness of the binder.

By mounting the sheets or cards in groups on a binder back, it is possible to provide a thick binder with the sheets or cards thereon more easily available, as it is necessary to turn to the group in which a particular sheet or paper would be, and then thumb through the sheets or cards of that particular group, without having to thumb through many more sheets, as would be the case with a binder made with but a single tier of rings.

Furthermore, the present invention makes it possible that when a binder is open the groups will lie substantially flatwise, without the margins of the sheets or cards along the rings sticking up or piling up in a manner to be unhandy. The present invention makes it easier to mount the sheets or cards in a binder as sheets or cards of one group may be applied to its rings and then the rings closed, the second group of sheets or cards may then be applied to the second tier of rings and the rings closed, and a third group of sheets or cards applied to the third group of rings, and so on, depending on the number of tiers of rings there are attached to the binder back.

It will be noted that Figures 1, 2 and 3 show three tiers of rings attached to a binder back. It is to be understood that the invention contemplates the use of two or more such ring tiers as the width of the binder may suggest and the number of sheets or cards per group as may be deemed expedient.

The backbones of the several tiers of rings,

heretofore mentioned, are preferably secured to the backs 10 of the binders by suitable adhesive material designated at 20, the character of which is well understood in the art.

Referring to Figures 4 and 5, a back 10 is equipped with a plurality of tiers of rings formed from a sheet of suitable material having a central backbone 21 and with a plurality of fingers on each side of the margins of the backbone maintained in parallelism, and designated at 22 and 23, the fingers 22 being on the left-hand side of the backbone as illustrated, with the fingers 23 on the right-hand side.

These fingers are crimped to provide a plurality of ring-like portions 24, 25, 26 and 27 in the fingers. The figures show the ring-like portions 24 and 25 as formed in the fingers 22 while the portions 26 and 27 are formed in the finger portions 23. The backbone 21 is suitably fastened to the backs 10 by adhesive 28, in permanent relation. Sheets or cards are then slipped over the free ends 30 and 31 of the fingers 22 and 23 and onto the ring-like portions 25 and 24 of fingers 22, and ring-like portions 27 and 26 of fingers 23. When the maximum number of sheets or cards or the like have been applied to the ring-like portions in the manner described, the free ends 30 and 31 of the fingers 22 and 23, respectively, are then stuck to the back by means of a suitable pressure sensitive adhesive or other suitable adhesives.

The portions of the several fingers between the inner and outer ring-like portions, designated at 32 and 33, may be stuck to the back in like manner.

It will thus be observed that utilizing the arrangement of Figures 4 and 5, four groups of sheets or cards may be attached to a back.

It will be observed that the present invention makes it possible to arrange sheets and cards in a loose-leaf binder in groups, thereby providing a thick binder with the maximum number of sheets and cards arranged so that when it is desired to find any particular sheet or card, the observer may select the group in which such sheet or card should appear and then thumb through that particular group until he finds what he wants.

It is quite obvious that the thickness of any group is dependent on the number of tiers of rings there are in the binder. For example, if there are two tiers, then the thickness of each group will not exceed one-half the thickness capacity of the binder. In like manner, if there are three tiers, then the thickness of every group will not exceed a third of the thickness capacity of the binder. With four tiers of rings the thickness of any one group will not exceed approximately one-quarter of the thickness capacity of the binder.

The invention has been described herein more or less precisely as to details, yet it is to be understood that the invention is not to be limited thereby, as changes may be made in the arrangement and proportion of parts, and equivalents may be substituted, without departing from the spirit and scope of the invention.

20 The invention is claimed as follows:
 A loose-leaf binder comprising a back having hinged covers, means providing a plurality of tiers of ring-like members on said back, said means including a member having a backbone portion complementarily shaped to said binder back and a plurality of fingers extending in parallel relation outwardly from each side of said backbone, said backbone being attached to said binder back, each of said fingers having a plurality of crimped inverted U-shaped portions providing ring-like loops in association with said back, each of said ring-like loops having sheet-receiving portions capable of receiving a plurality of sheets.

35 CHARLES EDWARD EMMER.
